RESISTANCE ELEMENT FOR VARIABLE
ELECTRICAL RESISTORS

John J. Mucher, Brooklyn, N. Y.

Application August 28, 1934, Serial No. 741,750

3 Claims. (CL 201—55)

This invention relates to variable electrical resistors of the type which embody a resistance element in the form of a film or coating of carbonaceous material applied to a flexible non-conductive base such as disclosed in my co-pending application, Serial No. 715,071, filed March 12, 1934 which has since issued as Patent 1,997,427, April 9, 1935.

In variable electrical resistors for use in delicate circuits such as employed as a volume control in radio receiving apparatus, it is essential that the surface of the resistance material be as near flat and as free from irregularities as possible in order to avoid erratic fluctuations or changes in the resistance value.

In variable electrical resistors now in general use, which embody a flexible resistance base in the form of a split ring with only the terminals thereof secured to the backing, the unsecured portion thereof between the terminals becomes distorted due to the absorption of moisture and the unequal expansion of the opposite surfaces thereof with a consequent warping or buckling thereof away from the backing which warping or buckling of the base and the resistance element thereon produces erratic fluctuations in the resistance when the contact is moved thereover and further frequently resulting in short circuiting.

The present invention, therefore, contemplates an electrical resistor of the type indicated, in which the film or coating of carbonaceous material is applied to an improved non-conductive base which is so constructed and arranged as to prevent buckling, warping or distortion thereof due to atmospheric or other conditions.

More particularly the invention resides in the provision of a resistance element comprising a thin flexible annular insulation base having a central opening and a coating of resistance material on one surface thereof partially surrounding and spaced from the opening and leaving an uncoated portion defining an insulation surface upon which an annular contact and its terminal element is seated to secure the resistance element in flat engagement with the backing member so as to prevent flexing or distortion of the resistance element.

With the above recited and other objects in view, which will be more fully described herein-after, reference is now made to the following specification and accompanying drawing in which there is illustrated one embodiment of the invention, while the appended claims cover variations and modifications thereof which fall within their scope.

In the drawing:

Fig. 1 is an enlarged inner end view of a variable electrical resistor, with the casing removed, constructed in accordance with the invention.

Fig. 2 is a similar view to Fig. 1 with the rotor removed.

Fig. 3 is a sectional view taken on a plane indicated on line 3—3 of Fig. 1, and illustrating the same applied to a mounting panel.

Fig. 4 is a perspective view of the improved resistance element.

Referring to the drawing by characters of reference, A designates generally a variable resistor which includes a resistance element B, comprising a thin flexible annular insulation base 8 of paper or other suitable material, and a carbonaceous resistance material composed of carbon, graphite or a mixture of both, together with a suitable binder which is coated or suitably applied to a portion of one surface of the insulation base in the form of a continuous arcuate strip 9 of a width to extend inwardly from the outer periphery of the base and terminating in an arcuate line 10 which line is spaced from and concentric to a central opening 11. The continuous arcuate strip 9 also terminates in radially disposed spaced end edges 12 and 13 extending inwardly from the outer periphery of the base to the arcuate line 10. This arrangement defines, between the central opening and the inner edge 10 of the carbonaceous resistance material, an uncoated annular insulation surface portion 14 and between the end edges 12 and 13 a radial uncoated insulation surface portion 15 forming a continuation of the annular uncoated insulation surface portion 14. The resistance element B is disposed flatly upon an insulation backing 16 to which it is secured by rivets 17 or other suitable means of connection and to the terminals 18 and 19 which project radially from the base, the inner ends of which are disposed upon and in electrical contact with the carbonaceous resistance material.

An annular contact member 20 is secured upon the uncoated portion of the insulation base concentric with the opening 11 and in spaced relation with the resistance material, and is provided with an angulated projection 21 which is anchored to the insulation backing 16 by a rivet 23 or other securing means. The annular contact member 20 is also provided with a radially projecting anchoring lug 24 which extends through an opening 25 in the uncoated portion 15 of the insulation base and is anchored or otherwise secured to the insulation backing 16. The annular contact member 20 thus clamps the resistance

element B in flat engagement with the backing member thereby preventing the same from buckling or warping due to atmospheric changes and eliminating distortion of the carbonaceous resistance material.

The insulation backing 16 has secured thereto a bushing 26 extending concentrically therethrough with its inner end crimped over upon the upper surface thereof. The bushing 26 is formed 10 with an enlarged flange 27 between which and the base 16 a washer 28 is interposed, which is keyed or otherwise secured to the bushing 26 to lock the washer against turning movement with reference to the bushing. The washer 28 is provided 15 with a lug 31 which is bent inwardly and is anchored in the insulation backing 16 to hold the backing against turning movement with reference to the washer and bushing 26. The washer is also provided with a radially projecting finger 32 20 which is bent at an angle for engagement within the recess 33 in a mounting panel 34 for holding the variable resistor against turning. The bushing is externally threaded and protrudes through an opening in the panel 34 for receiving a lock 25 nut 35 for mounting the variable resistor to the panel.

A shaft 36 is mounted for rotation in the bushing 26 and is formed with an annular groove 37 at its point of emergence from the bushing 26, 30 which groove is engaged by a split lock ring 38 for limiting the inward axial movement of the shaft. The inner end of the shaft is formed with an annular groove 39 in which groove a rotor 40 of insulation material is arranged. Disposed upon 35 the rotor 40 and arranged in the groove 39 is a washer 41 which is provided with an offset lug 42 for engagement in an opening 43 in the rotor and by which the rotor is keyed to the shaft 36, the inner end of the shaft being flanged upon 40 the washer 42 to firmly secure the washer and the rotor in the groove 39.

The rotor 40 has attached thereto a substantially U-shaped resilient wiper contact 44 disposed in confronting relation with the upper surface of 45 the annular contact member 20 and which is so tensioned that the intermediate or bight portion thereof frictionally contacts with the said annular contact member. The opposite face of the rotor has secured thereto a substantially U-shaped 50 contact arm 45, the terminals of which are secured to the terminal ends of the wiper contact 44 by means of conductor rivets 46 which pass through the rotor 40. The contact arm 45 is of greater length than the wiper contact 44 so that the medial or bight portion of the arm 45 overlies the resistance material on the insulation base 8. The rotor 40 is of generally circular formation, having a radially projecting enlargement 47 which is contoured to define oppositely disposed stop shoulders 55 48 and 49 adapted to engage with the extension 50 of the rivet head 23 to limit the turning movement of the rotor and shaft 36. The enlargement 47 is provided with a medial radially disposed notch 51 which registers with the medial 60 or bight portion of the contact arm 45 and receives an offset tongue 52, which is struck from the bight portion of the arm.

A non-resilient and non-deformable contact shoe or element 54 lies partly within the confines of the notch 51 and is provided in the plane upper surface thereof with a groove 55 which receives the tongue 52 of the contact arm 45 so that the said shoe or element 54 is urged by the inherent resiliency of the arm 45 into frictional engagement with the resistance on the insulation surface 8. The contact shoe or element 54 is also engaged by the side edges of the notch 51 to be moved by the contact arm 45 in an arcuate path over the resistance so as to vary the resistance between the terminal 21 and the terminals 18 and 19 respectively. 5

What is claimed is:

1. In a variable electrical resistor, a backing member, a resistance element including a flexible annular insulation base having a central opening and a resistance material applied to one surface of said base and extending partially around 20 the same and spaced from the central opening thereof to leave an uncoated portion, a contact member engaging against said uncoated portion for clampingly attaching the resistance element against the backing member and for preventing 25 flexing or distortion of the resistance element.

2. A resistance element for variable electric resistors which embody a backing member of insulation material and an annular fixed contact having a radial contact terminal carried by said 30 backing member, said resistance element comprising a thin flexible annular insulation base having a central opening and a coating of resistance material on one surface thereof partially surrounding and spaced from the opening and providing annular and radial uncoated insulation surface portions against which uncoated surface portions the annular fixed contact and radial terminal thereof are impinged to hold the resistance element in applied contact with the backing member so as to prevent flexing or distortion of the 35 resistance element.

3. In a variable electrical resistor, a rotatable shaft, a backing member fixedly secured concentrically with reference to the shaft, a resistance element comprising an annular insulation base of thin flexible paper having a central opening and a coating of resistance material on one surface thereof in the form of a continuous arcuate strip extending inwardly from the periphery of the base and terminating in an arcuate line spaced from and concentric with the central opening and defining between the central opening and the arcuate inner edge of the coated strip, an annular uncoated surface portion, an annular contact member overlying said uncoated surface portion and secured to said backing member with the insulation base fixedly supported upon the backing member concentric with said shaft, a resilient wiper contact, and a movable contact element mounted for movement by and with said shaft for engagement respectively with said annular contact member and said resistance material for varying the electrical resistance. 40

JOHN J. MUCHER.
